UNITED STATES PATENT OFFICE.

CHARLES LETTERI, OF COLUMBUS, OHIO.

SAFETY DEVICE FOR STEAM-BOILERS.

No. 869,000.

Specification of Letters Patent.

Patented Oct. 22, 1907.

Application filed April 24, 1907. Serial No. 369,938.

To all whom it may concern:

Be it known that I, CHARLES LETTERI, a citizen of the United States, residing at Columbus, in the county of Franklin and State of Ohio, have invented a certain 5 new and useful Improvement in Safety Devices for Steam-Boilers, of which the following is a specification.

The object of this invention is to provide improved means for preventing the explosion of steam boilers due to the exposure of the crown-plate to the direct 10 heat of the fire when, through the carelessness of the operator or through unavoidable circumstances, the water in the boiler has become dangerously low. It is a well-known fact that the greater number of boiler explosions are due to the weakening of the crown-plate under the conditions referred to, the plate becoming softened and caused to sag and break under 15 the pressure of the steam.

The invention consists briefly in the provision of means, in connection with the crown-plate or other 20 part of the boiler shell between the steam and combustion chambers, adapted to be weakened and collapsed under exposure of the direct heat of the fire thereon prior to the lowering of the water so as to expose the crown-sheet. The rupture and collapsing of 25 the device permits the liberation of the steam, whereby the pressure in the boiler is not only relieved but the liberated steam is directed upon the fire and deadens the same.

Embodiments of the invention are shown in the accompanying drawings, but the invention is not limited 30 to the precise construction and arrangement shown.

In said drawings—Figure 1 is a sectional view of a portion of a locomotive boiler showing the application of the invention thereto; Fig. 2 is a sectional view on an 35 enlarged scale showing portions of a crown-plate and roof-plate with crown-bolts and the safety device applied; Fig. 3 is a similar view showing a modified form of the safety device, and Fig. 4 is a bottom plan view of a section of the crown-sheet with the safety device 40 and crown-bolts applied.

In the several views 1 designates the crown-sheet of a steam boiler and 2 the roof or other companion sheet. These sheets are connected as usual by crown-bolts 3, 3. The safety devices are also located between the 45 crown and top sheets and comprise in the instance shown in Fig. 1 a hollow stem 4 threaded into the top sheet and more firmly held against longitudinal movement or displacement by means of a plug 5 driven into the end of the stem.

50 6 designates a bell or cup-shaped coupling fitted snugly into an opening in the crown-sheet and connected by means of fine threads 6^a with the stem 4. A bead or flange is also provided on the bell-shaped flange to prevent the device from pulling through the

crown-plate. It is apparent that the part 6 can be 55 threaded into the crown-sheet but the manner of attachment shown is preferred. The top of the coupling 6 adjacent the threads, as indicated at 6^b, is considerably thinner than the sides.

The purpose of the device is to relieve the steam 60 pressure before the crown-sheet has been damaged and to provide a quick-acting safety device. It will be seen that both the coupling and the tube are open to the direct heat from the fire, but so long as the coupling and the lower end of the tube are covered with water 65 they will remain unaffected by the heat of the fire. However, the instant they are uncovered and subjected to the steam pressure and the action of the intense heat the pressure of the steam will collapse the coupling and tend to blow it out into the fire. The heat 70 of the fire and the steam pressure also tend to reduce or elongate the lower end of the tube and loosen the connection, so that when the steam pressure is exerted on the top of the coupling the portion of the coupling engaging the stem is forced downward by 75 reason of the thin portion of the coupling and, even if the coupling should not be blown out of the opening in the crown-plate, the parts will be disengaged and an opening had through which the steam will pass into the fire box. It is obvious that this rupture of the 80 parts would take place while there was still water on the crown-sheet but at the time the water had become dangerously low.

It will be seen that the device not only effects the release of the pressure in the boiler but the escaping 85 steam is also directed upon the fire in the fire box and deadens the same. The escaping steam would necessarily have considerable force and would thus scatter and partly, if not wholly, extinguish the fire and thus remove liability of further injury to the boiler. 90

In the modification of the device shown in Fig. 3 the tube 7 is closed at its upper end and the bell-shaped coupling 8 is beaded at 8^a and 8^b on both sides of the crown-sheet. In this construction the softening of the parts and the pressure of the steam alone are relied upon 95 to collapse the structure and cause the severance of the parts 7 and 8 at their threaded junction.

What I claim and desire to secure by Letters Patent is:

1. A steam boiler having an opening in its shell between the steam and combustion chambers, a closure for said opening located within the boiler and secured to the shell at said opening and to a rigid part of the shell removed from the combustion chamber, said closure adapted to be ruptured when subjected to abnormal heat due to the lowering of the water in the steam chamber. 100

2. A steam boiler having an opening in its shell between the steam and combustion chambers, a hollow closure for said opening located within the boiler and comprising a cup-shaped portion secured to the shell at the opening and 110

a tubular portion connected with a rigid part of the shell removed from the combustion chamber, said closure adapted to be ruptured when subjected to abnormal heat due to the lowering of the water in the steam chamber.

5. 3. A steam boiler having an opening in its shell between the steam and combustion chambers, a hollow closure for said opening located within the boiler and comprising a cup-shaped portion secured to the shell at the opening and a portion connected with a rigid part of the shell removed

from the combustion chamber, said cup-shaped part being provided with a thin or reduced portion adapted to be ruptured when the cup-shaped portion is subjected to abnormal heat due to the lowering of the water in the steam chamber.

CHARLES LETTERI.
